UNITED STATES PATENT OFFICE.

JACOB F. KNORR, OF ORANGE, NEW JERSEY.

HAME.

SPECIFICATION forming part of Letters Patent No. 295,924, dated April 1, 1884.

Application filed August 18, 1883. (No model.)

To all whom it may concern:

Be it known that I, JACOB F. KNORR, a citizen of the United States, residing at Orange, in the county of Essex and State of New Jersey, 5 have invented new and useful Improvements in Hames, of which the following is a specification.

This invention has for its object to provide a simple and efficient metallic hame of novel construction; and the invention is fully illustrated in the accompanying drawings, in which—

Figure 1 represents a front view. Fig. 2 is a rear view. Fig. 3 is a cross-section on the 15 line $x\ x$, Fig. 1. Fig. 4 is a like section on the line $y\ y$, Fig. 1. Fig. 5 is a like section on the line $z\ z$, Fig. 1.

Similar letters indicate corresponding parts. The letter A designates the body of a hame 20 which is shaped like a trough, it being widest at the edge or open side thereof, which constitutes the rear of the article; and it will be readily seen that by this shape the hame-body is adapted to be cast without the use of a core, while it 25 possesses the strength and lightness in weight of a tubular core.

On the edges of the trough-shaped hame-body A are cast lips or offsets B, which tend to widen such edges, and thus form a superior 30 bearing for the hame on the horse-collar, the inner lip moreover serving to hold the hame in position on the collar by entering the usual recess in the collar.

In the hollow part of the trough-shaped 35 hame-body A are cast a series of transverse webs, C, which are flush or nearly so with the edges thereof, and act as braces for strengthening the body.

At the proper part of the hame is located the draft-plate D, which is sunken into the 40 edges of the trough-shaped body flush or nearly so therewith, to preserve the proper bearing of such edges on the collar, and which is held in place by rivets e, passing through the lips B.

The strap loop or staple F is secured in place 45 by inserting its ends between the hame-body and the draft-plate, the rivets g passing through the draft-plate, the loop or staple, and the outer offset, B, of the hame-body.

To the upper end of the hame-body is fastened the top H. This top has a downward projection, I, which overlaps the hame-body, and which is shaped to entirely cover that portion of the body which is exposed when the hame is put on a collar. 50

What I claim as new, and desire to secure by Letters Patent, is—

1. A hame consisting of a trough-shaped body, A, the draft-plate D, sunken into the edges of the body and riveted to such edges, and the 60 strap-loop F, having its ends inserted between the body and draft-plate and secured thereto, substantially as described.

2. The combination of the trough-shaped hame-body A, having offsets B at its edges, 65 with the draft-plate D sunken into the hame-body, and rivets attaching the edges of the draft-plate to the offsets, substantially as described.

In testimony whereof I have hereunto set my 70 hand and seal in the presence of two subscribing witnesses.

JACOB F. KNORR. [L. s.]
